DOOR PULL

Harry B. Neal and Raymond V. Burnham, Atlanta, Ga.,
assignors to Anaconda Aluminum Company, Louisville,
Ky., a corporation of Montana

Filed Dec. 14, 1964, Ser. No. 83,022

Term of patent 14 years

(Cl. D10—8)

FIG. 1

FIG. 2

FIG. 3

FIG. 4

FIG. 5

FIG. 1 is a front perspective view of a door pull embodying our new design;

FIG. 2 is a front elevation thereof;

FIG. 3 is a side elevation thereof as seen from the left side of FIG. 2;

FIG. 4 is a side elevation thereof as seen from the right side of FIG. 2; and

FIG. 5 is a top plan view thereof.

We claim:

The ornamental design for a door pull, substantially as shown.
